MORRIS M. TITTERINGTON, OF BROOKLYN, NEW YORK, ASSIGNOR TO THE PROSPERITY COMPANY, INC., OF SYRACUSE, NEW YORK, A CORPORATION OF NEW YORK

GARMENT OR IRONING PRESS

Application filed July 16, 1926, Serial No. 122,824. Renewed July 8, 1929.

This invention relates to pressing machines and more particularly to steam power presses operated by fluid pressure and which is adapted for use in garment pressing and laundry 5 ironing work and for other purposes.

An object of the invention is to produce a power jaw for presses, a jaw simple in design and construction and embodying a diaphragm-type power producing motor means 10 operated by steam or other fluid pressure.

A further object is to produce a novel power jaw with fluid-pressure motor means placed within the jaw together with an automatic throttle valve which is actuated by the 15 operating means used to open and close the press, the result being to automatically start the operation of the motor means after the press has reached closed position and thereby attain final high compression between the 20 jaws of a press.

Other objects of the invention will be understood from a consideration of the accompanying drawings and following description. Changes may be made without departing 25 from the principle of the invention.

Figure 1 illustrates a side fragmentary view of a garment press with the power jaw shown in cross section thereby disclosing a disk type expansion diaphragm employed to 30 actuate a compression plate to produce jaw compression after the press is closed.

Figure 2 shows an example of control valves, a throttle or inlet valve and an exhaust valve, by which the flow of steam to and from 35 the diaphragm is controlled to stop and start jaw compression.

Figure 3 is a fragmentary plan view of the power press jaw with a part of the pressing face or compression plate broken away to expose the corrugated disk diaphragm mounted therebelow.

Figure 4 illustrates a longitudinal sectional view of the pressing member or power jaw in which is incorporated the improved power 45 and the pressure producing motor means.

Referring now to the drawings for a further description of the invention, there is shown a press frame 10 on which is mounted 50 press lever 11 pivoted at 12 on the frame and a press head jaw 13 is carried on the forward

end of the press lever 11 and is adapted to be closed on the work after it is spread upon the lower jaw or buck 15. Any suitable operating means, such as the press lever 11 or other suitable means, may be employed to 55 execute the press opening and closing action.

The pressing head 13 as well as the buck 14-15 are usually steam heated and when this type of press is used, the steam is conveyed to the press through a steam feed pipe 60 15' and the same steam which is available to heat the press is also used for operating the compression motor means which makes for economy in heating and power operating the press because one and the same medium is 65 used.

Referring further to the improved construction of one of the jaws, as for example the buck or lower jaw, there is shown a stationary jaw plate, support or mounting plate 70 14 anchored to the frame 10 and thereupon is mounted a rigid and relatively movable compression plate 17. The two members 14 and 17 together constitute the lower press jaw and one part thereof is movably relatively to and on the other to produce jaw compression for high pressure laundry ironing work or for pressing seams and the like in the manufacture of garments. Within the composite jaw structure there is mounted a 75 simple disk diaphragm expansion motor to perform all the work incident to producing high jaw compression. The compression plate 17 may be made hollow if desired for the purpose of receiving the steam into a steam heating chamber 16 to heat the compression plate and for other use if desired.

The compression plate may be made with a depending marginal flange 18 having clearance from and between a corresponding upturned flange 19 made integral on the stationary jaw plate 14. The flanges 18 and 19 or other means guide the compression plate 17 up and down in relation to the stationary jaw plate 14 and clearance is left between the guide flanges 18 and 19 to permit the compression plate 17 to undergo a slight oscillating or wobbling motion on, about, or in relation to the other plate 14 in order that its front or rear edge may travel more 100

or less than its other edge thereby accommodating itself to unevenness and irregularity of seams or other work to be pressed between the jaws. Furthermore one end of the compression plate 17 may be thrust or forced up higher or lower than the other end due to unevenness of the work between the jaws. In this way compensation of the meeting faces of the coating jaws on uneven irregular work of varying thickness is accomplished in a simple way with simple press construction.

One or more upstanding ribs or flanges 21 are made in one of the jaw members, in this instance in the stationary jaw plate 14, and a flat type corrugated flexible disk diaphragm 22 has its outer edge mounted on the rib 21 and sealed in by a ring 23 or other suitable means. In this way a diaphragm steam receiving expansion chamber 24 is formed pressure tight between the corrugated disk diaphragm 22 and the wall of the stationary jaw plate 14.

It is noted that the diaphragm 22 forms one head of the steam expansion chamber 24 and the solid wall of the plate 14 forms the other head of the steam expansion chamber and that the circular rib defines the wall of the steam expansion chamber. This chamber 24 possesses a small volumetric capacity and a small amount of steam is therefore required to fill it.

In the drawings there is shown a pressing jaw or buck provided with several, in this instance two, spaced corrugated disk diaphragms, one being mounted in the jaw toward each end thereof, or any suitable number of fluid diaphragms are used for ordinary ironing and pressing operations. The size or area of the press jaws and the compression required determines the number of and the diameter of the disks incorporated into the press jaw.

The outer edge of the corrugated disk diaphragm is hermetically sealed on one of the jaw members, in this instance on the stationary jaw plate 14, and the center of the disk diaphragm normally rests in contact with the compression plate 17. The expansion of the disk therefore lifts upwardly on the compression plate with great force to press it against the head and thus produce jaw compression.

A feature of this power press is that the motor means operates off of the same fluid pressure, steam, as used to heat the press jaws. The center of the diaphragm disk may if desired be sealed onto the inside wall of the compression plate 17 by any suitable means as for example, by a nut 26. In the present instance, the nut 26 may to advantage be made hollow and is screwed into a steam passage leading to the heating chamber 16 to permit steam to circulate through the heating chamber. The nut 26 secures

the center of the disk diaphragm 22 to one jaw member and the perimeter thereof being secured to the other jaw forms the steam tight expansion chamber 24 aforesaid into which steam is received to force upwardly 70 on the flexible diaphragm during the pressing operation thereby moving the pressing plate 14 upwardly with great force.

The flexible plate or disk type diaphragms 22, one or more thereof being used, in one or both jaws, possesses sufficient flexibility inherent therein as to permit considerable flexure or distortion in its wall. The flexure in the diaphragm is increased somewhat by the circular concentric corrugations spun into 80 the disk 22 and when steam is turned into the compression chamber 24, a substantial pressure is exerted upwardly on the diaphragm 22 and steam at the same time flows through the passage 28 to heat the pressing plate 17 85 heretofore mentioned.

It is significant that this power press jaw is compact, that the motor means 22 is placed adjacent and directly in contact with the rigid compression plate 17, and there are no 90 intervening parts between the rigid press plate and steam motor means.

Steam pipes 30 transmit steam to one or more compression chambers 24 and a feed pipe 31 connects the pipes 30 with the steam supply pipe 15' heretofore mentioned. Automatic valve control means may be used to open the steam into the diaphragm chambers 24 if desired so that when the press head 13 is closed, the diaphragms 22 automatically expand to produce jaw compression.

A steam valve 33 is mounted in the pipe 31 and is preferably spring closed and embodies a valve stem 34 which closes upwardly against or in line with a valve push rod 35, the upper end of which is pivotally connected at 36 to the press lever 11. As the press lever 11 moves downwardly, the valve plunger 35, held vertically by a parallel motion arm 37, impinges the valve stem 34 and opens the valve 33 thereby permitting steam to flow into the pipe 31 and hence to the one or more steam expansion chambers.

A steam exhaust valve 39 is mounted in pipe line 31 and a control handle 40 is connected to the exhaust valve 39 which is normally held open as by a spring 41 or other suitable means so that said valve is always open as shown in Figure 2 in order that steam may flow past the valve 33 through the exhaust valve 39 and directly to the one or more compression chambers 24 immediately the head 13 has reached lowermost position in contact with the work on the compression plate 17. The spring 41 therefore holds the valve 39 open as shown, with the waste or exhaust pipe 50 closed, the result of which is to leave free both hands of the operator so that he may quickly adjust the work and draw the head 13 down thereupon and in- 130

stantly the throttle valve automatically opens to permit a flow of steam to the diaphragm expansion chamber which produces instant jaw compression which continues until the operator turns the exhaust valve 39 to permit discharge of steam from one or more expansion chambers through exhaust pipe to atmosphere, whereupon the expansive force of the disk diaphragm subsides and jaw pressure is released.

The fact that a flat type corrugated flexible disk diaphragm is used makes for economy in structure and economy in steam. The steam expansion chamber 24 is relatively small. Furthermore, the movement of the compression plate 17 is very little, just sufficient to compress the work. This is due to the fact that the operator physically brings the head 13 down in close engagement with the compression plate 17 and the work thereon before the diaphragm is acted on by steam. The compression plate 17 therefore moves upwardly a distance substantially equal to the compressional and contracational ability of the work which is very little in actual movement or travel of the plate 17 on the other plate 14. Therefore the movement of the diaphragm, i. e., its flexure is exceedingly limited which is an ideal working condition conducive to long life of this improved motor means.

It is to be noted that the diaphragm 22 performs a triple function in that it affords a compensated wobbling motion of the compression plate 17 in relation to the stationary buck plate 14 and hence the compression plate 17 is mobile and adjusts itself in function when under pressure to unevenness in the work as to seams and other irregularities in the work to be pressed; likewise the diaphragm with its passage 28 affords a flexible connection of a new kind between the two fluid chambers 16 and 24 and it is evident that there are no moving parts other than the flexure of the diaphragm itself; and finally there is the motor-means function of the diaphragm in that it produces the necessary power to press the work under high jaw compression between the head 13 and press-buck plate 17. Hence is explained the triple functions of the diaphragm.

Steam heat or fluid pressure for other purposes is readily transmitted from one chamber to another thru the aperture 28 of the sealed fluid pressure diaphragm 22 and thus is eliminated movable parts such as stuffing boxes and the like usually employed to convey fluid pressure from a stationary part to a movable part. At the same time the diaphragm admits of mobility and adjustment of the compression plate to accommodate unevenness met with in the work as already explained. The simple motor means shown performs all three functions separately or together and the construction is of the simplest

kind including in reality only one diaphragm member for the several purposes named.

What I claim is:

1. A power press jaw comprising, two plates of substantially equal area movable one relatively to the other, one of which constitutes a rigid compression plate and the other constituting a mounting plate adapted to be secured in service position on a frame, means for loosely maintaining the rigid compression plate on the mounting plate during the relative motion, and motor means within the jaw to execute with great force the relative motion aforesaid. 75

2. A power press jaw comprising, two plates of substantially equal area movable one relatively to the other, one of which constitutes a rigid compression plate and the other constituting a mounting plate adapted to be secured in service position on the frame, 80 means for loosely maintaining the rigid compression plate on the mounting plate during the relative motion, and a fluid-pressure actuated diaphragm carried within the jaw between the two plates to execute the relative motion and constituting a single-phase sheet-metal flexible member the perimeter of which is sealed to one plate to form a fluid-expansion chamber and the central portion of which expands against the other plate. 90

3. A jaw for power presses comprising, a stationary support member, a rigid compression plate movably mounted thereon, and a flat flexible sheet metal expansible diaphragm interposed between and engaging the support member and compression plate to form a fluid-expansion chamber whereby said plate and member are forced apart upon the reception of fluid pressure into the expansion-chamber. 100

4. A jaw for power press comprising, two relatively movable members one of which is a rigid compression plate, means to guide one plate on the other in relative motion, a flat sheet-metal expansion diaphragm mounted 110 between the members and having its periphery sealed onto one member, said diaphragm forming one head of a fluid expansion chamber in the jaw, and means to transmit fluid pressure into the expansion chamber whereby the diaphragm applies force to the rigid compression plate. 115

5. A jaw for power presses comprising, two plates placed together for relative motion and a space formed therebetween, a rib raised on one plate within the space, a flat sheet-metal diaphragm having its outer edge sealed onto the raised rib, said diaphragm forming a movable head of an expansion chamber in the 125 jaw and adapted to act against the other plate, said circular rib forming the wall of the expansion chamber, the plate which is integral with the rib forming the stationary head of the expansion chamber, and means for 130

- feeding a pressure fluid to the expansion members, one of which is a compression plate, said plate resting upon and in direct contact with the other member, and a flexible metallic diaphragm placed between the two members and sealed to one member at its periphery to form a fluid expansion chamber between the diaphragm and said one member and acting against the other member.
6. A power jaw for presses comprising, a stationary mounting plate, a rigid compression plate carried therewith, an integral guide flange formed on the perimeter of each plate and slidably contained one in another to form a space between the plates, and a fluid expansion diaphragm mounted in the space between the two plates to act on the compression plate.
7. A power jaw for presses comprising, a stationary mounting plate, a compression plate movably mounted thereon, an integral flange formed on the perimeter of each plate and slidably contained one in another to form a space, a rib raised on the stationary mounting plate between the two plates and forming the wall of an expansion chamber and said mounting plate forming one head of the expansion chamber, and a flat sheet-metal diaphragm having its outer edge secured to the rib and forming the movable head of the expansion chamber.
8. A power press jaw comprising, a stationary plate, a compression plate movably mounted thereon, a marginal guide flange on one of the plates overhanging the margin of the other plate to form a closed space, several raised ribs formed on one plate within the jaw at intervals, and a flat sheet-metal diaphragm sealed on each rib between the plates to form expansion chambers, and means to transmit fluid pressure to the several chambers thereby enabling the diaphragms to forcibly move the compression plate.
9. A power press jaw comprising, a compression plate provided with a steam heating chamber, a mounting member on which rests the compression plate, a flexible and flat sheet-metal diaphragm disposed between the mounting member and compression plate to force the plate relatively away from the mounting member, said diaphragm forming a steam reception expansion chamber, a passage leading from the expansion chamber to the heating chamber, and means sealing the central portion of the diaphragm to the compression plate around the passage, which passage is formed through the diaphragm to connect the two chambers.
10. A power press jaw comprising, a hollow compression plate embodying a fluid heating chamber with a fluid passage leading thereto, a stationary mounting member on which the compression plate rests, a diaphragm disk placed between the compression plate and mounting member and having its outer edge secured to the mounting member to form a fluid-expansion chamber between the diaphragm and the mounting member, and a hollow nut screwed into the aforesaid passage securing the center of the diaphragm to the compression plate.
11. A power press jaw comprising two
12. A power press jaw comprising two closely spaced plates, a circular flange raised on one plate between the two plates, a flexible circular corrugated flat sheet-metal expandible diaphragm having its outer edge sealed onto the flange of the one plate to form an expansion chamber, said diaphragm expansibly engaging its center against the other plate, and means to supply fluid pressure to the chamber.
13. A power press jaw comprising two members, one of which is a compression plate, said plate resting upon and in direct contact with the other member, a flat flexible metallic diaphragm placed between the two members and sealed to one member at its periphery to form a fluid expansion chamber between the diaphragm and said one member and acting against the other member, said compression plate being provided with a fluid receiving chamber, means in the compression plate to convey fluid from the expansion chamber to the receiving chamber, and said means leading through the flexible diaphragm from one chamber to another.
14. A press jaw comprising a diaphragm and a stationary support therefor, and a movable compression plate engaging the diaphragm, the diaphragm consisting of a substantially flat flexible sheet metal member which is rendered flexible by circular corrugations therein concentrically formed whereby the corrugations increase in diameter from the center outwardly; and means to seal the periphery of the diaphragm to the press jaw to form a fluid pressure expansion chamber, the corrugations of which flex to afford a bulging motion of the diaphragm whereby the compression plate is moved in relation to the stationary support.
15. A press jaw comprising a diaphragm and a stationary support therefor, and a movable compression plate engaging the diaphragm, the diaphragm consisting of a substantially flat flexible sheet metal member which is rendered flexible by circular corrugations therein concentrically formed whereby the corrugations increase in diameter from the center outwardly; and means to seal the periphery of the diaphragm to the stationary support to form a fluid pressure expansion chamber between the diaphragm and support, means to transmit fluid pressure into the expansion chamber, whereby the concentric corrugations of the diaphragm flex under expansion of the fluid pressure to bulge the diaphragm against the compression plate to

move the latter in relation to the stationary support.

16. A press jaw comprising two main parts one of which is a movable compression plate to directly engage the work and the other is a stationary support, the two parts being mounted in proximate relation, a single piece sheet-metal flat-disk circular-corrugated diaphragm disposed between the two parts, the center of the diaphragm engaging one part and the periphery thereof engaging the other part, and means to seal the periphery of the single piece diaphragm to one part to form a fluid-pressure expansion chamber.

17. A press jaw comprising a movable compression plate provided with a fluid-receiving chamber, a stationary support for the movable compression plate, a diaphragm placed therebetween and including at least one circular sheet-metal flat-and-concentrically-corrugated member the central portion of which is adapted to bulge toward and move the compression plate, and a fluid passage made through that portion of the diaphragm which is adapted to bulge, the passage thereof leading to the fluid-receiving chamber of the compression plate, and means to seal the periphery of the sheet-metal diaphragm to the stationary support to form a fluid-pressure expansion chamber.

18. A press jaw comprising a movable compression plate, a support therefor, and a single sheet-metal circular-corrugated disk-type diaphragm disposed therebetween and in engagement with the plate and support, the support including a shallow fluid-expansion chamber and means to transmit fluid pressure thereinto, means to seal the periphery of the diaphragm to the periphery of the fluid-expansion chamber and hence the central portion of the diaphragm is adapted to bulge outwardly from the fluid-expansion chamber and move the compression plate in relation to the support, said compression plate being provided with a fluid-receiving chamber, and means to transmit fluid pressure into the fluid-receiving chamber from the fluid-expansion chamber whereby the same fluid is used in both chambers and the latter means including a passage formed centrally through the diaphragm portion which engages the compression plate.

19. A press jaw comprising two main parts constituting a rigid compression plate and a stationary support therefor, the two parts being placed together to produce a compact structure, a flat sheet-metal flexible member forming an expandible diaphragm placed between and in contact with both parts, and the perimeter of the diaphragm being sealed to one part to make a fluid-expansion chamber whereby one side of the chamber is formed by the flexible diaphragm

and the other side of the chamber is rigid and is formed by a wall of the press jaw.

20. In a press having cooperating press jaws and operating means to open and close the press, one of the jaws including a compression plate and a support therefor, a fluid-pressure motor means placed between the plate and support and engaging both, means including a valve to transmit fluid pressure to the motor means to produce jaw compression, means actuated by the operating means to automatically open the valve when the press is closed, and means to exhaust the fluid pressure from the motor means to relieve the jaw compression.

21. In a garment or laundry press, coacting press jaws, operating means to open and close the jaws, and one jaw including a pair of relatively movable parts one of which is provided with a fluid receiving chamber, a flat disk-type flexible diaphragm disposed between and engaging the two parts, said diaphragm being apertured, and means to seal the edges of the diaphragm aperture to one part with the aperture in communication with the fluid receiving chamber, whereby fluid pressure may be passed thru the diaphragm aperture into the fluid receiving chamber.

22. In a garment or laundry press, coacting press jaws and operating means to work a jaw to open and close the press, one of the jaws comprising two main parts and including a support member and a compression plate movable in relation to said support member, said support member being provided with a fluid chamber, said movable compression plate being provided with a fluid chamber, a combination motor means and flexible fluid connection made between the fluid chamber of the movable compression plate and the fluid chamber of the support member including a flat disk-type flexible diaphragm disposed between said two main parts, means sealing the periphery of the diaphragm to one part, means sealing the center of the diaphragm to the other part, said diaphragm being provided with an opening therein placing the fluid chambers in communication with each other, whereby the diaphragm acts as a fluid expansion motor means to produce pressure by moving the compression plate against the opposing jaw and acts as a flexible connection by conveying fluid from one part to the other.

23. In a garment or laundry press, coacting press jaws, operating means to open and close the jaws, and one jaw including a pair of relatively movable parts one of which is provided with a fluid receiving chamber, a flat disk-type flexible diaphragm disposed between and engaging the two parts, whereby one part is rendered mobile and is adapted to undergo a compensated action in relation to the other to accommodate itself to irregularities in the work being pressed, said dia-

phragm being apertured, and means to seal the edges of the diaphragm aperture to one part with the aperture in communication with the fluid receiving chamber, whereby fluid pressure may be passed thru the diaphragm aperture into the fluid receiving chamber, and the other part also including a space enclosed by the diaphragm and which forms a fluid expansion chamber to receive fluid pressure to expand the diaphragm to produce jaw compression.

In testimony whereof I affix my signature.
MORRIS M. TITTERINGTON.
